UNITED STATES PATENT OFFICE.

FREDERICK R. GOOLMAN, OF BINGHAMTON, NEW YORK, ASSIGNOR TO HARRIS PLAYER PIANO COMPANY, OF BINGHAMTON, NEW YORK, A CORPORATION OF NEW YORK.

AUTOMATIC MECHANISM FOR PIANO-PLAYERS.

1,054,837.

Specification of Letters Patent. Patented Mar. 4, 1913.

Application filed June 28, 1911. Serial No. 635,870.

To all whom it may concern:

Be it known that I, FREDERICK R. GOOLMAN, a citizen of the United States, residing at Binghamton, in the county of Broome and State of New York, have invented certain new and useful Improvements in Automatic Mechanism for Piano-Players, of which the following is a specification.

The present invention relates to automatic piano players of that general type which are controlled by the passage of a perforated music sheet over a duct bridge, the primary object of the invention being the provision of novel means for automatically bringing a new spool into position and removing the old spool as soon as the latter has finished playing.

A further object of the invention is the provision of a magazine adapted to contain a number of spools, means being associated with the magazine for bringing the various spools successively into position for playing, and removing them from position when they have finished playing.

A still further object of the invention is the provision of a magazine for automatic piano players which may be constructed to hold either a large or small number of spools, which operates in a positive and reliable manner to move the spools through the magazine and bring them successively into action, and which automatically re-winds each spool while the following spool is being played.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a magazine for automatic piano players constructed in accordance with the present invention, the mechanism for setting the piano player in operation and stopping the same being shown diagrammatically. Fig. 2 is a top plan view of the device. Fig. 3 is a longitudinal vertical sectional view on the line 3—3 of Fig. 2. Fig. 4 is an enlarged plan view of the auxiliary switch and a portion of the resetting mechanism. Fig. 5 is a

detail view of the resetting cams and the main lever of the resetting mechanism. Fig. 6 is a detail view of one end of the shield which is employed for preventing the kicker from injuring the music sheet. Fig. 7 is a sectional view through the outer end of one of the music sheets showing the spring which is applied thereto. Fig. 8 is a detail sectional view of the resetting mechanism, the parts being shown in full lines in the position assumed when releasing a spool which has just finished playing, and by dotted lines in the position assumed when a new spool has just dropped into position. Fig. 9 is an enlarged sectional view through the duct bridge, and Fig. 10 is an enlarged view showing the springs for preventing backward movement of the spools through the magazine.

Corresponding and like parts are referred to in the following description and indicated in all the views of the drawings by the same reference characters.

Referring to the drawings, the numerals 1 designate a pair of castings or plates which have a spaced and parallel relation to each other and constitute the sides of the main frame upon which the mechanism is mounted, the said plates being rigidly connected by cross bars 2. These side plates 1 of the main frame are provided upon their inner faces with corresponding endless runways 3 adapted to receive the ends of the spools 4. Each of the runways is shown as comprising a lower horizontal portion 3^a and an upper horizontal portion 3^b, the said horizontal portions of the runway being connected at the rear end of the magazine by a curved portion 3^c, and at the forward end of the magazine by a curved portion 3^d. The portions 3^a, 3^b, and 3^c of the runway are filled with the spools 4 which are moved step by step rearwardly within the portion 3^a of the guideway, around the portion 3^c, and forwardly upon the portion 3^b, the various spools being brought successively into action as they drop from the forward end of the portion 3^b of the runway to the forward end of the portion 3^a thereof. It may here be noted that the spools in the upper portion 3^b of the runway merely rest loosely thereon so that they can readily be removed and replaced by other spools when desired.

Referring to Fig. 3 of the drawing the spool 4^a which is in position for playing

rests upon supporting rolls 5 and 6, the former being fixed in position and being continuously rotated while the player is in operation, while the latter merely acts as an idler and is journaled upon the arms 7 projecting downwardly from a rock shaft 8. The music sheet 9 is drawn downwardly from the spool 4^a over the tracker-bar or equivalent element, herein termed a duct bridge 10, and finally drops upon an apron 11 where it rolls up loosely on itself. The feed rolls 12 and 13 for drawing the music sheet from the spool are located under the duct bridge 10, the feed roll 12 being rigid with a shaft 14 which is positively driven when the player is in operation, while the feed roll 13 is journaled upon the arms 7 and merely serves to press the music sheet 9 against the roll 12. The duct bridge 10 is of the usual construction and is designed to be connected to some suitable player mechanism such as that disclosed in Patent No. 917,288 which was granted to me on April 6, 1909. This duct bridge is shown 25 as suspended by means of a pair of hooked hangers 15 which removably engage one of the cross bars 2.

Referring further to Fig. 3, it will be observed that the spool 4^b which was previously played is resting upon an idler 16 and a rewinding roller 17, the top of the said spool being engaged by a positioning roller 18 which may be suitably weighted or otherwise caused to bear upon the spool 4^b so as to hold the same in contact with the rewinding roller 17. The positioning roller 18 is journaled between a pair of rearwardly extending arms 19 which are pivotally connected to the frame at 20 to admit of the positioning roller being moved up and down, the downward movement of the said roller being limited by lips 21 which project laterally from the arms 19 and are adapted to engage ribs upon the main frame.

45 The rock shaft 8 which carries the arms 7 is also provided with a crank arm 22 which is connected by a rearwardly extending link 23 to an upwardly extending arm 24 upon a second rock shaft 25. A coil spring 26 engages this arm 24 and normally tends to draw the same rearwardly so as to rotate the rock shaft 8 and swing the arms 7 into the position indicated by full lines on Fig. 8. Rigid with the second rock shaft 25 and 55 preferably integral with the arm 24 is the resetting lever 27, the said lever being shown as extending forwardly from the rock shaft 25 and having the end thereof extended upwardly to provide a support upon which the 60 kicker 28 is pivotally mounted. The forward end of the kicker 28 normally projects downwardly into the path of the spools, while the upper end thereof is provided with a roller 29 adapted to be engaged by a cam 65 30 upon a resetting shaft 31. This reset-

ting shaft 31 is journaled upon the sides 1 of the main frame and is also provided with a second cam 32 adapted to engage a roller 33 upon the main lever 27. The resetting shaft 31 is normally locked against rotation with the cams in the position indicated in Fig. 5, the cam 30 being out of engagement with the roller 29 of the kicker and the forward end of the kicker being held away from the spool 4^b by means of a spring 34 connecting the kicker to the resetting lever, while the roller 33 of the lever 27 is engaged by the steep portion 32^a of the cam 32. The said lever 27 is thereby held in a depressed position against the action of the spring 34, 80 and the arm 24 swung forward so as to move the arms 7 of the rock shaft 8 into the position indicated upon Fig. 3. For the purpose of bringing a new spool into position, the resetting shaft is given one complete revolution. The initial movement of the resetting shaft moves the steep portion 32^a of the cam 32 away from the roller 33 so that the said roller can enter the depressed or shallow portion 32^b of the cam and permit the lever 90 27 to swing upwardly, thereby moving the kicker 28 out of the path of the spools and also operating through the arm 24 and link 23 to rock the shaft 8 and swing the arms 7 into the position indicated by full lines on Fig. 8. The supporting roll 6 is thereby moved away from the supporting roll 5 so as to drop the spool 4^a, and the feed roll 13 is moved away from the feed roll 12 so as not to obstruct the downward passage of the spool 4^a. A continued rotation of the shaft 31 brings the roller 33 of the resetting lever 27 into engagement with a substantially circular portion 32^c of the cam 32 so as to partially depress the lever 27 and thereby swing the arms 7 forward a sufficient amount so that the supporting rolls 5 and 6 will engage the next spool as soon as it is forced over upon the same. The cam 30 then engages the roller 29 of the kicker 110 28 and moves the rear end of the kicker upwardly, thereby causing the forward end of the kicker to engage the spool 4^a and move it forcibly into the position previously occupied by the spool 4^b, all of the spools in the magazine being thereby moved forward one step, and that spool at the forward end of the upper portion of the runway being forced over upon the supporting rolls 5 and 6. The supporting roller 5 rotates the spool 115 in such a direction as would wind the music sheet thereon, and while the spool is thus rotating the hooked projection 35 at the end of the music sheet is engaged by a resetting hook 36 which was moved upwardly between the feed rolls. This resetting hook projects upwardly from a rod 37 connecting a pair of levers 38 which extend rearwardly along opposite sides of the main frame and are pivotally connected thereto at inter- 125 130

mediate points between their ends, as indicated at 39. The rear ends of these levers 38 are connected by links 40 to crank arms 41 at opposite ends of the resetting shaft 31, the said crank arms being so positioned with relation to the before mentioned cams as to move the resetting hook 36 upwardly when the feed rolls are separated and the new spool is forced into position. In order to move the nose of the resetting hook 36 forwardly and insure a proper engagement thereof with the hooked projection upon the music sheet, a spring 42 may be utilized, the said spring being secured to a cross bar 43 and bearing loosely against the back of the hook member as it is raised. A continued movement of the resetting shaft 31 operates the levers 38 to draw the resetting hook 36 downwardly below the feed rolls, and the steep portion 32^a of the cam 32 is then again brought into engagement with the roller 33 so as to force the lever 27 downwardly and thereby produces a further rotation of the rock shaft 8 so as to cause the feed roll 13 to hold the music sheet tightly against the feed roller 12. At this point, attention may be directed to the fact that the end spool upon the upper portion 3^b of the runway is prevented from dropping accidentally upon the spool 4^a by means of a shoulder 3^c at the bottom of the runway. When the spool is forced forwardly it passes readily over this shoulder, although it is held thereby against prematurely dropping into position. It will further be observed that the resetting shaft 31 is provided with a timing disk 44 and a gear wheel 45, the said timing disk being formed with a notch or opening 46 into which one end of a slidably mounted counter-shaft 47 normally projects. This counter-shaft is journaled upon one of the side pieces 1 of the main frame and a bracket 48 projecting therefrom, and a pinion 49 upon the counter-shaft is thrown into mesh with the gear wheel 45 when the counter-shaft is moved to withdraw the end thereof from the opening of the timing disk, the said pinion being out of engagement with the gear wheel while the end of the counter-shaft is within the opening of the timing disk. A shipper lever 50 which has a bell crank formation is pivotally mounted upon the bracket 48 and engages the counter-shaft 47 to slide the same within its bearings, a spring 51 being applied to the shipper lever for normally holding the counter-shaft in engagement with the opening of the timing disk. An electric switch 52 is also mounted upon the bracket 48, and the switch lever 53 is formed with an extension 53^a which engages the counter-shaft 47 so that the said switch is closed when the shipper lever 50 is moved to retract the counter-shaft from the opening of the timing disk. The engagement of the counter-shaft with the

opening of the timing disk normally locks the resetting shaft 31 against rotation and holds the various members in the position indicated in Fig. 3, while when the counter shaft is withdrawn from the opening 46 of the timing disk and the pinion 49 thereon brought into mesh with the gear wheel 45, the said counter-shaft can be turned to rotate the resetting shaft, the end of the counter-shaft being held frictionally against the side of the timing disk by the action of the spring 51 so that as soon as one revolution has been completed the counter-shaft will again enter the opening 46 and prevent further movement of the resetting shaft.

As indicated more clearly in Fig. 7, the free end of each of the music sheets 9 has a spring strip 54 applied thereto, the said spring strip normally tending to assume a coiled position so as to prevent the music sheets from unwinding from the spools while the spools are passing through the magazine, and also forming a nucleus or center about which the unwound music sheet rolls as it is drawn from the spool and dropped upon the apron 11. The before mentioned hooked projection 35 is preferably formed by returning the outer end of the spring strip 54.

An electric motor 55 is utilized for operating the piano player, and power is transmitted through the medium of the pulleys and belts 56 to a main drive shaft 57 which is provided with a gear wheel 58. A chain or belt 59 passes around this gear wheel and also engages a gear wheel 60 which is rigid with the supporting roller 5, a gear wheel 61 which is rigid with the counter-shaft 47, a gear wheel 62 which is rigid with the rewinding roller 17, and a gear wheel 63 which is rigid with the feed roll 12. Electric current is supplied to the motor 55 through the wires 64, and a switch 65 is employed for opening and closing the circuit. This switch is normally held in an open position by means of a catch 66, and is connected to a pneumatic 67 by means of a rod 68. It will also be observed that wires 69 lead from opposite sides of the main switch 65 to the auxiliary switch 52, and that the pneumatic 67 is connected by a pipe 70 to a second pneumatic 71; the said second pneumatic being connected by a rod 72 to one end of a lever 73 which is pivoted upon one side of the magazine, the upper end of the lever being connected by a link 74 to the shipper lever 50.

The various parts of the mechanism are normally in the position indicated in Fig. 3 with the main switch 65 held in an open position by means of the catch 66, the spool 4^a being in position for playing while the spool 4^b is in position for being rewound. When the switch 65 is released, either manually or by dropping a coin upon a pan 75 carried by the catch 66, the said switch is

closed by means of the spring 76. The motor is then started and the various elements driven by the chain 59 set in motion. The feed rolls draw the music sheet from the spool 4^a over the duct bridge 10 so as to actuate the player mechanism in the usual manner, while the rewinding roller 17 revolves the spool 4^b to wind up the music sheet which was previously played. It will 10 also be observed that the supporting roll 5 turns in such a direction as to resist unrolling of the music sheet from the spool 4^a, thereby acting to produce tension in the music sheet and hold it firmly against the 15 duct bridge. The counter-shaft 47 is also revolved, but merely acts as an idler, since the pinion 49 thereon is out of engagement with the gear wheel 45. As soon as the end 20 of the music sheet is reached, an opening therein uncovers a certain duct 77 in the duct bridge and admits air into a pipe 78 leading to the pneumatic 67. Air is then exhausted from the pneumatics 67 and 71 so as to collapse the same, and this action of 25 the said pneumatic 67 draws the switch blade 65 back into engagement with the catch 66 so as to open the switch, while the collapsing of the pneumatic 71 swings the lever 73 so as to actuate the shipper lever 50 30 and pull the counter-shaft 47 out of the opening 46 of the timing disk 44. The pinion 49 upon the said counter-shaft is simultaneously brought into mesh with the gear wheel 45 and the auxiliary switch 52 closed. The motor 55 continues to run as 35 long as this auxiliary switch is closed and the various parts of the machine are still driven as before. The motion of the counter-shaft 47, however, is now imparted to 40 the resetting shaft 31 until the said shaft has completed one revolution, when the counter-shaft 47 again enters the opening 46 of the timing disk 44 so as to lock the same against motion. This sliding movement of the counter-shaft also serves to 45 open the auxiliary switch 52 so as to completely shut off the supply of electric current to the motor 55. The single revolution of the resetting shaft 31, however, acts as 50 has been previously described to bring a new spool in position for playing and drop the old spool down upon the rewinding roller. In order to prevent the kicker 28 from injuring the music sheet, a guard plate 55 59, which is illustrated more clearly in Fig. 6, may be carried by the arms 7. The machine is now ready to play the new spool as soon as the main switch 65 is again closed, and this operation will be repeated indefinitely, the various spools being forced step by step around the runway and brought successively into action. In order to prevent 60 backward movement of the spools through the magazine, spring detents 80 may be applied to the sides 1 of the frame so as to 65

bear frictionally against the ends of the spools and engage depressions 81 therein. These spring detents are shown more clearly in Fig. 10, and it will be observed that the spools are perfectly free to move forward 70 when the kicker 28 is set in action, although they are held securely against any backward movement.

Having thus described the invention, what I claim as new and desire to secure by Letters Patent, is:—

1. An automatic piano player including a magazine constructed to receive a number of spools, means for automatically extracting the spools from the magazine and bringing them into position for playing, and means for automatically returning the spools to the magazine after playing.

2. An automatic piano player including a magazine formed with a runway adapted to receive a number of spools, means for automatically extracting the spools from the magazine and moving them through the runway and bringing them successively into position for playing, and means for automatically returning the spools to the magazine after playing.

3. An automatic piano player including a magazine adapted to receive a number of spools, automatic means for extracting the spools from the magazine and bringing them successively into position for playing, means for bringing the spools from the position for playing into a position for rewinding, means for rewinding the spools, and means for automatically returning the rewound spools to the magazine.

4. An automatic piano player including a magazine constructed to receive a number of spools, means for extracting the spools from the magazine and bringing them into position for playing, feeding means, means for bringing the music sheet of the spool in position for playing and into engagement with the feeding means, and means for automatically returning the played sheet and its spool to the magazine.

5. An automatic piano player including a magazine constructed to receive a number of spools, means for bringing the spools successively into position for playing, feed rolls, means for separating the feed rolls and bringing them together, a music sheet engaging member, and means for moving the same between the feed rolls while the latter are separated to engage the music sheet and draw it between the rolls.

6. An automatic piano player including a magazine constructed to receive a number of spools, the music sheets upon the spools being provided at the ends thereof with projections, means for bringing the spools successively into position for playing, feed rolls, means for separating the feed rolls when a new spool is brought into position for play-

ing and then bringing them together again, a hook member, and means for causing the hook member to pass between the feed rolls while the same are separated and engage the 5 projection upon the end of the music sheet so as to draw the end of the music sheet between the feed rolls before the same are brought together.

7. An automatic piano player including a 10 magazine constructed to receive a number of spools, supporting elements for positioning a spool being played, means for moving the spools upon the supporting elements, means for drawing the music sheet from the spool 15 being played, means for separating the supporting elements to drop the spool after it has finished playing, and means for then forcing the spool back into the magazine.

8. An automatic piano player including a 20 magazine constructed to receive a number of spools, a pair of supporting elements adapted to position a spool being played, means for bringing the spools from the magazine upon the supporting elements, means for drawing the music sheet from the spool being played, means for separating the supporting elements to drop the spool after it has finished playing, means for rewinding the spool, and means for again forcing the 30 spool into the magazine.

9. An automatic piano player including a 35 magazine constructed to receive a series of spools, spaced supporting elements for positioning a spool being played, feed rolls for unwinding the music sheet from the spool being played, means for separating the supporting elements and feed rolls when the spool has finished playing so as to drop the spool, means for rewinding the spool, means 40 for forcing the spool back into the magazine and bringing a new spool upon the supporting elements, and means for bringing the music sheet of the new spool into engagement with the feed rolls.

45 10. An automatic piano player including a magazine adapted to receive a number of spools, supporting elements adapted to position a spool being played, a pair of feed rolls, swinging arms carrying one of the supporting elements and also carrying one of the feed rolls, means for moving the arms when the roll has finished playing to separate the supporting elements and the feed rolls so as to drop the spool, means for 50 rewinding the spool and moving the same back into the magazine so as to bring a new spool upon the supporting elements, and means for engaging the music sheet upon the new spool and bringing it between the 55 feed rolls.

60 11. An automatic piano player including a magazine constructed to receive a number of spools, supporting elements adapted to position a spool being played, a pair of feed rolls, means for separating the supporting

elements and feed rolls to drop the spool when it has finished playing, the said supporting elements and feed rolls being then partially returned to normal position so that the feed rolls are separated and the supporting 70 elements will engage a new spool, and then finally brought into normal position with the feed rolls bearing against each other, means for forcing the old spool back into the magazine and bringing a new spool 75 upon the supporting elements while the feed rolls are still separated, and a reciprocating member mounted to pass between the feed rolls and engage the music sheet upon the new spool so as to draw it between the said 80 feed rolls before the same are finally brought together.

12. An automatic piano player including a magazine constructed to receive a number of spools, supporting elements for positioning a spool being played, automatic means for separating the supporting elements to drop the spool after it has ceased playing, and a kicker for forcing the old spool back 85 into the magazine and bringing a new spool 90 into position upon the supporting elements.

13. An automatic piano player including a magazine constructed to receive a number of spools, means for supporting a spool in position for playing, means for releasing 95 the spool when it has finished playing, and a kicker for forcing the old spool back into the magazine and bringing a new spool into position for playing.

14. An automatic piano player including a 100 magazine formed with a runway adapted to receive a number of spools, supporting elements adapted to position a spool being played, a pair of feed rolls, swinging arms carrying one of the positioning elements and one of the feed rolls, automatic means for moving the arms to separate the supporting elements and feed rolls so as to drop the spool when it has finished playing, the said arms being then partially returned 105 to normal position so that the supporting elements will engage a new spool although the feed rolls are still separated, and then finally returned to position with the feed rolls bearing against each other, means for rewinding the old spool and forcing it back into the runway, a new spool being thereby brought upon the supporting elements while the feed rolls are still separated, and a reciprocating member adapted to pass between the feed rolls and engage the music sheet of the new spool so as to draw it back 110 between the feed rolls before the same are finally closed.

15. An automatic piano player including a 115 magazine formed with a runway adapted to receive a number of spools, positioning means for engaging a spool to be played, means for withdrawing the music sheet from the spool being played, means for re- 120 125 130

leaving the spool and dropping the same when it has finished playing, a rewinding roller, and a kicker for bringing the spool into engagement with the rewinding roll 5 and moving the spools through the magazine so as to bring a new spool into engagement with the positioning means.

16. An automatic piano player including a magazine adapted to receive a series of 10 spools, supporting elements for positioning a spool while being played, a pair of feed rolls, swinging arms carrying one of the supporting elements and also one of the feed rolls, a resetting shaft, automatic means for 15 throwing the resetting shaft into action while the spool is playing, means actuated by the resetting shaft for swinging the arms to separate the supporting elements and drop the old spool, and means also actuated 20 by the resetting shaft for forcing the old spool back into the magazine and bringing a new spool upon the supporting elements.

17. An automatic piano player including a magazine adapted to receive a number of 25 spools, supporting elements adapted to position a spool being played, feed rolls, swinging arms carrying one of the supporting elements and also one of the feed rolls, a rewinding roll, a resetting shaft normally 30 locked against movement, means for releasing the resetting shaft and turning the same when the spool has finished playing, means actuated by the resetting shaft for moving the swinging arms to separate the supporting 35 elements and feed rolls so as to drop the spool, a continued movement of the resetting shaft moving the arms partially back into position so that the supporting elements will engage a new spool although 40 the feed rolls are still separated, while the final movement of the resetting shaft again brings the feed rolls together, independent means actuated by the resetting shaft for 45 forcing the old spool back into the magazine in engagement with the rewinding roller, a new spool being thereby dropped upon the supporting elements, and a reciprocating member actuated by the resetting shaft and passing between the feed rolls 50 while they are still separated so as to engage the music sheet of the spool and draw it between the feed rolls before they are finally brought together.

18. An automatic piano player including 55 a magazine constructed to include a number of spools, supporting elements adapted to position a spool being played, feed rolls for withdrawing the music sheet from the spool being played, a rewinding roller, a resetting 60 shaft, a cam upon the resetting shaft, means actuated by the cam for separating the supporting elements and feed rolls to release the spool when it has finished playing, the supporting elements and feed rolls being 65 then partially returned to position so that

the supporting elements will engage a new roll although the feed rolls are still separated, and then finally brought back to normal position with the feed rolls bearing against each other, a second cam upon the 70 resetting shaft, a kicker actuated by the second cam for moving the old spool into the magazine in engagement with the rewinding roller and bringing a new spool upon the supporting elements, and a reciprocating 75 member actuated by the resetting shaft, the said reciprocating member passing between the feed rolls while they are separated and engaging the music sheet of the new spool to draw it between the feed rolls before the said 80 feed rolls are finally brought together.

19. An automatic piano player including a magazine constructed to receive a number of spools, supporting elements for positioning a spool while being played, feed rolls for 85 drawing the music sheet from the spool being played, swinging arms carrying one of the supporting elements and also one of the feed rolls, a resetting shaft, a cam upon the resetting shaft, a resetting lever actuated by 90 the cam, an operative connection between the resetting lever and the before mentioned arms, means for normally locking the resetting shaft against motion, automatic means for releasing the resetting shaft when the 95 spool has finished playing, the cam upon the resetting shaft first moving the resetting lever to swing the arms to separate the feed rolls and supporting elements and drop the spool, while a continued movement of 100 the cam actuates the resetting lever to partially return the arms to normal position so that the supporting elements will engage a new spool although the feed rolls are still separated, the said feed rolls being brought 105 together by the final action of the cam upon the resetting lever, means actuated by the resetting shaft for forcing the old spool back into the magazine and bringing a new spool upon the supporting elements, and a reciprocating member also actuated by the resetting shaft, the said reciprocating member 110 passing between the feed rolls while they are still separated and engaging the music sheet of the new spool so as to draw it between the feed rolls before they are finally closed.

20. An automatic piano player including a magazine constructed to receive a series of 115 spools, supporting elements adapted to position a spool while being played, a pair of feed rolls, swinging arms carrying one of the supporting elements and also one of the feed rolls, a rewinding roll, a resetting shaft normally locked against turning, a pair of 120 cams upon the resetting shaft, a resetting lever actuated by one of the cams, a kicker mounted upon the resetting lever and adapted to be actuated by the opposite cam, means for automatically releasing the reset- 125 130

- ting shaft and throwing the same into motion when a spool has finished playing, the initial movement of the first mentioned cam serving to move the before mentioned arms 5 to separate the feed rolls and supporting elements so as to drop the old spool, while a continued movement of the cam partially returns the arms to normal position so that the supporting elements will engage a new 10 spool although the feed rolls are still separated, the feed rolls being brought together when the arms are returned to normal position by the final movement of the cam, while the other cam operates the kicker to move 15 the old spool into engagement with the rewinding roll and bring a new spool upon the positioning elements, and a reciprocating hook member actuated by the resetting shaft, the said reciprocating hook member 20 passing between the feed rolls while the same are still separated and engaging the music sheet of the new spool so as to draw the same between the feed rolls before the same are finally closed.
21. An automatic piano player including a magazine constructed to receive a number of spools, positioning means for supporting a spool being played, a kicker for forcing an old spool back into the magazine and 25 bringing a new spool into position for playing, a resetting shaft, means actuated by the resetting shaft for releasing a spool which has finished playing and operate the kicker, a timing disk upon the resetting shaft, a 30 slidably mounted shaft normally engaging the timing disk to lock the resetting shaft against motion, means for automatically withdrawing the sliding shaft from engagement with the timing disk when a spool has 35 ceased playing, and gearing for transmitting power to the resetting shaft, the said gearing being thrown into mesh by the movement of the sliding shaft.
22. An automatic piano player including 40 a magazine constructed to receive a number of spools, a resetting shaft, means actuated by the resetting shaft for bringing the spools successively into action and removing them therefrom, a gear wheel upon the re- 45 setting shaft, a timing disk upon the resetting shaft, a sliding shaft normally engaging the timing disk to lock the resetting shaft against motion, the said sliding shaft being formed with a pinion which is 50 normally out of mesh with the before mentioned gear wheel, and automatic means for sliding the said shaft to withdraw the same from engagement with the timing disk and bring the pinion into mesh with the gear 55 wheel when a spool finishes playing.
23. An automatic piano player including 60 a magazine adapted to receive a number of spools, supporting means adapted to position a spool while being played and constructed to turn the spool in such a direc- 65 tion as to oppose the unwinding thereof, the music sheet upon each spool being provided with a projection, feeding means for withdrawing the music sheet from the roll, a reciprocating hook member, means for moving the hook member into the path of the projection upon the revolving spool so as to engage the projection of the music sheet thereon and bring the music sheet into engagement with the feeding means, means for releasing the spool when it has finished 70 playing, and means for moving the old spool back into the magazine and bringing a new spool into position for playing.
24. An automatic piano player including 75 supporting means adapted to position a roller and constructed to revolve the same in such a direction as to oppose the unwinding thereof, the music sheet upon the spool being provided with a projection, a pair of feed rolls, means for separating the feed rolls, and a reciprocating hook member adapted to move between the feed rolls and engage the projection upon the music sheet 80 so as to draw the said music sheet between the feed rolls.
25. An automatic piano player including 85 supporting means for positioning a spool to be played and rotating the said spool in such a direction as to initially oppose the unwinding thereof, the music sheet upon the spool being provided with a projection, feeding means for unwinding the music sheet from the spool, and means co-operating with the projection upon the music sheet 90 for bringing the said music sheet into engagement with the feeding means.
26. An automatic piano player including 95 a spool, a music sheet provided along a portion of its free end with a spring member, said spring member being under normal coiling tension, and acting as means for starting the loose coiling of the music sheet upon itself into the form of a loose roll after being played, supporting means for 100 positioning the spool, means for withdrawing the music sheet from the spool for playing, and rewinding means for rewinding the loose roll back onto its spool.
27. An automatic piano player including 105 a spool, a music sheet having a spring strip applied to the free end thereof, and provided with a projection adapted to be engaged for forcibly unwinding the music sheet, said spring strip being under normal coiling tension, supporting means for positioning the spool, means for withdrawing the music sheet from the spool, and rewinding 110 means.
28. An automatic piano-player including 115 a music sheet, supporting means for positioning a spool having the said music thereon, a spring strip normally under coiling tension attached to the music sheet, means for withdrawing the sheet music from the 120 spool.
29. An automatic piano-player including 125 a music sheet, supporting means for positioning a spool having the said music thereon, a spring strip normally under coiling tension attached to the music sheet, means for withdrawing the sheet music from the 130 spool.

spool, and guide means engaging the sheet music after it has been played and passed beyond the feeding rolls to aid the spring strip in causing the sheet music to roll loosely upon itself.

29. An automatic piano player including a holder, a plurality of single unattached spools adapted to loosely rest in the holder and to be singly and independently removable, replaceable and interchangeable, each of said single rolls containing its own note sheet, means for singly bringing a spool into playing position and means for introducing the note sheet into operative relation with the tracker-bar of the piano playing mechanism.

15 30. An automatic piano player including

a holder, a plurality of single unattached spools adapted to loosely rest in the holder and to be singly and independently removable, replaceable and interchangeable, each of said single rolls containing its own note sheet, means for singly bringing a spool into playing position, means for introducing the note sheet into operative relation with the 25 tracker-bar of the piano playing mechanism, and means for returning the spool to the holder after playing.

In testimony whereof I hereunto affix my signature in the presence of two witnesses. 30

FREDERICK R. GOOLMAN.
